UNITED STATES PATENT OFFICE.

ELIJAH D. PARROTT, OF GOLDEN DALE, WASHINGTON.

CARBURETER.

SPECIFICATION forming part of Letters Patent No. 615,100, dated November 29, 1898.

Application filed March 25, 1898. Serial No. 675,148. (No model.)

To all whom it may concern:

Be it known that I, ELIJAH D. PARROTT, of Golden Dale, in the county of Klickitat and State of Washington, have invented a new and Improved Carbureter, of which the following is a full, clear, and exact description.

The invention relates to apparatus for manufacturing gas in which gasolene is evaporated by the use of an air-pump.

10 The object of the invention is to provide a new and improved apparatus, which is simple and durable in construction, arranged to maintain the same strength of gas throughout the generating process, to consume the 15 gasolene in a uniform manner according to the number of lights in use, to prevent the formation of frost inside of the generating devices, and to prevent freezing of the gas-mains between the lights and the carbureter.

20 The invention consists of novel features and parts and combinations of the same, as will be described hereinafter and then pointed out in the claims.

Reference is to be had to the accompanying 25 drawing, forming a part of this specification and which represents a sectional side elevation of the improvement.

The apparatus is housed in a suitable building A and is provided with a gasolene-storage 30 tank B, provided on its top with a filling-opening B' and formed with a false bottom B² for producing a gasolene-supply chamber B³ in the lower part of the storage-tank. A pipe B⁴ extends from the chamber B³ into the lower 35 end of the tank B, and said pipe is provided at its lower end with a valve B⁵, controlled by a float B⁶, swimming on the liquid contained in the chamber B³. By the arrangement described the chamber B³ receives its supply of 40 gasolene from the tank B, and at the same time a uniform level of the gasolene is maintained in the said chamber by the arrangement of the float B⁶ and the valve B⁵, controlled from the float.

45 From the chamber B³ leads an outlet-pipe C, controlled from a gasometer, as hereinafter more fully described, for regulating the flow of the gasolene from the chamber B³ through the pipe C, according to the amount of gas 50 generated. The lower end of the pipe C is connected with a pipe D, containing a valve D' and extending through the wall of the

building A to a small housing A', arranged on the outside of the building. The pipe D within the housing A' extends downward and opens into a T F', formed on the end of a coil F, arranged within a vessel F², located in the building A and set on a drip-can G or other suitable support. The lower end of the coil F terminates in a T F³, from which leads in 60 a downward direction a pipe F⁴ to the said drip-can G, so that any gasolene or other liquid matter not changed into gas in the coil F can float to the drip-can G.

From the upper end of the T F³ leads a 65 pipe F⁵ into an air-pump H of any approved construction and actuated by a drum and weight I or other suitable means. The air-pump H discharges into a pipe J, which leads to a stand-pipe J', discharging into the 70 gasometer-bell K, mounted in the usual manner in the gasometer-tank K', supported with-in the building A.

From the stand-pipe J' leads a gas-main L to connect with the burner in which the generated gas is used in the usual manner. From the gas-main L leads a branch pipe L' to the housing A', and located within the latter are a valve L² and a burner L³, arranged directly under the T F', which latter is also connected 80 with an air-supply pipe N, extending into the building A and then back again into the housing A', and has within the building a regulating-valve N' and a check-valve N², and in the housing A' the pipe N is provided with a hood 85 N³, located above the burner L³ and the T F', to receive air heated by the flame issuing from the burner L³.

Now it is evident that by the arrangement described the gasolene can flow through the 90 pipes C and D to the T F' and air can pass to the T F' in a heated condition from the hood N³ and pipe N, and as both the air and the gasolene are heated by the said T F' it is evident that the gasolene is evaporated and 95 at the same time mixed with the inflowing heated air. The gas flows through the evaporating-coil F to be cooled, preferably by water contained in the tank F².

As the pump H is in motion the gas is readily drawn in by the pump from the coil and forced through the pipe J to the stand-pipe J' and to the gasometer, and also to the gas-main L for consumption. The surplus gas

accumulates in the gasometer-bell K, which consequently rises in the liquid contained in the gasometer-tank K'.

The position of the valve C', that of the valve N', and of the valve L' in the pipe L' is regulated by the rising and falling of the bell, and for this purpose the following arrangement is made: The top of the gasometer-bell K is provided with a rod O, containing adjustable collars O' O², between which works one end of a lever P, fulcrumed on a bracket P', carried by the gasometer-tank K'. The lever P is pivotally connected by a link Q with a lever Q', fulcrumed on a bracket Q², carried by the tank B, and the said lever Q' engages a rod R, held to the lever by two nuts R', screwing on the threaded end of the rod and abutting against the top and bottom edges of the lever Q'. The rod R extends through a pipe B⁷, having a suitable stuffing-box, into the chamber B³, to connect at its lower end with the arm C² of the valve-stem for the valve C'. The lever P is also connected with a link S, having connection with an arm N⁴ on the valve-stem of the valve N', and the lower end of the said link S is reduced, as at S', for carrying adjustable collars S², between which operates the arm L⁵ on the stem of the valve L⁴. Now when the gas accumulates in the gasometer-bell K the latter moves upward, and in doing so imparts a swinging motion to the lever P, which motion is transmitted by the link Q to the lever Q' to lift the rod R and shut off the valve C'. At the same time the swinging motion of the lever P causes the link S to close the valves N' and L⁴ and regulate the flow of air to the pipe N and the flow of gas through the pipe L' to the burner L³. When the gasometer-bell K sinks on using the gas stored therein, then the several valves are again proportionately opened to insure generation of gas in the manner previously described, it being understood that the amount of gas generated is regulated according to the number of lights connected with the gas-main L. The several levers P Q' and links Q and S have adjustable connections with each other to permit of setting the regulating devices according to the number of lights in use.

The housing A' is preferably arranged on the outside of the building to prevent explosions, said housing being provided with a suitable air-inlet A² and an air-outlet A³. If desired, the gasoline may be directly fed from the pipe C into the upper portion of the coil F, and for this purpose the valve D' is closed and a valve D³ in a branch pipe D² is opened, so that the gasoline can flow from the pipe C through the branch pipe D² into the upper part of the coil F, as will be readily understood by reference to Fig. 2. Normally, however, the valve D³ is closed, and the valve D' is opened for leading the gasoline to the T F' to be heated, so as to insure a ready evaporation of the gasoline.

By having the burner L³ for heating the T F' no frost is liable to form inside of the gen-

erator-coil F, and, if desired, hot air may be sent through the main L to prevent freezing thereof. This is done by closing the valves D' and D³ and heating the air passing from the pipe N into the coil F, the air being pumped by the pump II through the pipe J into the main L between the lights and the carburetor to prevent freezing of the main.

It will be further understood that by the arrangement described the same strength of gas is maintained throughout the generating process, as the valves for controlling the flow of the gasoline and air are perfectly controlled by the gasometer-bell K.

Having thus fully described my invention, I claim as new and desire to secure by Letters Patent—

1. An apparatus for manufacturing gas, comprising a gasoline-supply pipe, an air-supply pipe connecting with the said gasoline-supply pipe, means for heating the pipes at the junction, a coil connected at one end with the said supply-pipe, an air-pump connected with the other end of the coil, and a gasometer into which the air-pump discharges, substantially as shown and described.

2. The combination of a gasoline-supply tank, a gasoline-supply pipe leading from said tank, an air-supply pipe connecting with the said gasoline-supply pipe, a burner for heating the said pipes, means for cooling the gas, a gasometer, and an air-forcing device for delivering the gas to the gasometer, substantially as described.

3. An apparatus for manufacturing gas provided with a gasoline-supply tank, a valved supply-pipe leading from the gasoline-supply tank, a valved air-supply pipe communicating with the gasoline-supply pipe, means for heating the said pipes, a gasometer, means for forcing the gas into the gasometer, and means controlled from the said gasometer and connected with the valves in the said pipes to regulate the flow of air and gasoline, substantially as shown and described.

4. In a gas apparatus, a valve-controlled gasoline-supply pipe, a valve-controlled air-supply pipe opening into the gasoline-supply pipe, a valve-controlled gas-pipe provided with a burner located at the junction of the air-supply and gasoline-supply pipes, a gasometer, a lever actuated by the movement of the gasometer, and connections from the said lever to the valves in the gasoline-supply pipe, the air-supply pipe and the gas-pipe, to regulate the flow of air, gasoline and gas, substantially as shown and described.

5. An apparatus for manufacturing gas, comprising a gasoline-storage tank, a gasoline-supply tank below the storage-tank, a gasoline-supply pipe leading from the supply-tank, an air-supply pipe opening into the gasoline-supply pipe, means for heating the pipes at the junction, a coil connected at its upper end with the gasoline-supply pipe, an air-pump connected with the lower end of said coil a gasometer into which said air-pump

discharges, a drip-receptacle located below the coil, and a pipe connecting the lower end of the coil with the drip-receptacle, substantially as shown and described.

6. An apparatus for manufacturing gas, comprising a gasoline-tank having a float-controlled valved inlet-pipe, a generating-coil a valved pipe connecting one end of the coil with the said tank, an air-pump connected with the other end of the coil, a gasometer into which the said pump discharges, and means controlled by the said gasometer and connected with the valve in the said valved pipe to regulate the flow of gasoline, substantially as shown and described.

7. An apparatus for manufacturing gas, comprising a gasoline-tank having a float-controlled valved inlet-pipe, a generating-coil connected at one end by a valved pipe with the said tank, an air-pump connected with the other end of the coil, a gasometer into which discharges the said pump, means controlled by the said gasometer and connected with the valve in the said valved pipe, and an air-supply pipe connected with the said coil having a valve also controlled by the said means, substantially as shown and described.

8. The combination with an air-pump, and a gas-main, of a stand-pipe connected with the air-pump and the gas-main, a burner, and an air-supply pipe adapted to be heated from the said burner and connected with the said air-pump, to permit of forcing heated air into the gas-mains, substantially as shown and described.

35

9. An apparatus for manufacturing gas, comprising a gasoline-tank having a float-controlled valved inlet-pipe, a generating-coil connected at one end by a valved pipe with the said tank, an air-pump connected with the other end of the coil, a gasometer into which discharges the said pump, means controlled by the said gasometer and connected with the valve in the said valved pipe, a burner under the junction of the air-supply pipe with the coil and gasoline-supply pipe, and a valve for controlling the flow of the gas to the burner, the valve being controlled by the said means, substantially as shown and described.

10. The combination with a gasoline-tank, a valve-controlled gasoline-supply pipe leading from the said tank, a valve-controlled air-supply pipe opening into the gasoline-supply pipe, and a coil connected at one end with the gasoline-supply pipe, of an air-pump connected with the other end of the coil, a gasometer into which discharges the said pump, a gas-main leading from said gasometer, a valved branch pipe leading from said gas-main and provided with a burner located at the junction of the gasoline-supply pipe and air-supply pipe, and means controlled by the gasometer for operating the valves in the gasoline-supply pipe, the air-pipe and the branch pipe leading to the burner, substantially as shown and described.
